John E. Hubbell

UNITED STATES PATENT OFFICE.

PHILIP D'H. DRESSLER, OF CLEVELAND, OHIO, ASSIGNOR TO AMERICAN DRESSLER TUNNEL KILNS, INC., OF NEW YORK, N. Y., A CORPORATION OF NEW YORK.

METHOD OF AND APPARATUS FOR GASIFICATION.

Application filed April 10, 1920, Serial No. 372,970. Renewed May 9, 1925.

My present invention consists in an improved method and apparatus for gasification. A primary object of the invention is to avoid troubles from carbon deposits when coal is distilled in a chamber so arranged and operated that the distillation heat is transmitted to the coal, wholly or largely by convection currents of the chamber atmosphere which comprises the gases of distillation, said currents being heated by contact with hot bodies which may be the fire heated walls of the distillation chambers or combustion chambers or other heated bodies in the distillation chamber. By the term coal as used herein I mean to include peat and other carbonaceous materials as well as ordinary coals.

In distilling coal in the manner just described there is a tendency for the hydrocarbons distilled out of the coal to "crack", on contact with the hotter portions of the surfaces of the chamber heating bodies with a resultant deposit of a hard carbon coating on said surfaces which cannot be readily cut or burned away, and which tends to increase in thickness until it materially reduces the amount of heat which the coated bodies can give to the chamber atmosphere.

I avoid deposits of carbon on the chamber heating bodies, in accordance with the present invention by mixing steam with the distillation gases contacting with the hotter portions of the heating bodies. The conditions which cause the hydrocarbons to crack will also cause the steam to combine with carbon according to one or both of the following reaction formulæ:

At relatively low temperatures the carbon and steam will react wholly or mainly in accordance with formula (A) at relatively high temperatures, the reaction will be wholly or mainly in accordance with formula (B), and at certain intermediate temperatures substantial amounts of both CO and CO₂ will be formed. The temperatures and other conditions controlling the reactions are well known and need not be further explained herein.

Under suitable conditions, the tendency will be for these reactions to take place by the combination of the oxygen of the steam with the carbon set free in the cracking of the hydrocarbons before this carbon has been

deposited, so that carbon deposits are thereby prevented. If and when such deposits occur, they may be removed by directing streams of steam against them. By localizing the steam introduction to the particular portions of the chamber where there is a tendency to carbon deposits, the hot bodies can be kept free of such deposits with the use of an amount of steam, which is relatively small and will not create any substantial tendency to lower the temperature of the distillation chamber as a whole. Of course the heating up and disassociation of the steam absorbs some heat but this is compensated for, more or less, by the hydrogen and carbon monoxide products. In some cases I contemplate the use of relatively large amounts of steam and the quantitative production of water gas. In some cases, also I contemplate the prevention or removal of carbon deposits by the use of air or CO₂ in place of steam as the decarbonizing agent.

The various features of novelty which characterize my invention are set forth in the annexed claims. For a better understanding of my invention, however, reference should be had to the accompanying drawings and descriptive matter in which I have illustrated and described preferred form of embodiment of my invention.

Of the drawings Fig. 1 is a somewhat diagrammatic, longitudinal sectional elevation;

Fig. 2 is a transverse section taken on the line 2—2 of Fig. 1; and

Fig. 3 is a view taken similarly to Fig. 2, illustrating a modification.

Figs. 1 and 2 of the drawings show a distillation chamber AA, in the form of a tunnel kiln. The distillation chamber AA has refractory walls B, of masonry with a kieselguhr insulation B¹. Benches C extend along the length of the major portion of the chamber at opposite sides of the pathway for the trucks D transporting coal through the chamber. Preferably the trucks D are provided with shallow trays or shelves D¹ on which the coal is placed. The chamber is provided with double doors E at its entrance end, and with similar doors F (of which only one is shown) at its exit end, to permit the periodic insertion and removal of trucks without any appreciable influx of air or escape of distillation gases. On the benches C are mounted combustion chambers H, in which combustion is initiated and through which the prod-

- ucts of combustion travel. Connected to the combustion chambers proper are pipes I through which the products of combustion pass to a flue J at the entrance end of the kiln.
- 5 The flue J is connected to a stack or other draft producing device not shown. Suitable known provisions, conventionally indicated at h, are made for the introduction of air and combustible gas to the combustion chambers at the ends of the latter, remote from the flue J. Between the exit-end of the kiln and the adjacent ends of the combustion chambers is a gas cooling system K which may be of any suitable or usual type, and as shown is 15 adapted for the heating of water and the generation of steam, the latter collecting in the steam and water drum K¹.
- 10 The kiln chamber is shaped to provide a gas collecting space above the passageway for the goods which is divided by transverse partitions A into a series of compartments open at their lower ends to the goods passageway. Each of these compartments is provided with an outlet A¹⁰ in the roof of the 20 chamber, through which the distillation gases collecting in the compartment may be withdrawn. The combustion chambers H are of the type commonly employed in the well known Dressler tunnel kiln and advantageously have their walls formed of hollow tile. The open ended passages H¹ in the walls of the combustion chambers form channels through which the gases forming the atmosphere of the kiln chamber ascend and 25 are heated. These gases, enter the channels through the openings immediately above the benches C and issuing from the channels through the upper outlets into the coal passageway in the general manner indicated by 30 the arrows in Fig. 2. The special features above described employed to adapt an ordinary Dressler kiln as shown for example in Patent No. 1,170,428, for use in the continuous distillation of coal were not invented by 35 me, but by Conrad Dressler and are disclosed and claimed in his Patent No. 1,509,196.
- 40 For the purpose of the present invention I provide passages L in the benches C which extend upward and open into channels H¹ in the walls of the combustion chambers adjacent the goods pathway. The passages L in each bench C are connected at their lower ends to a channel L¹ extending longitudinally of the bench, and preferably divided into 45 separate longitudinal sections with a supply passage L² for each section, running to the side of the kiln and connected to a corresponding steam supply pipe L³. Steam may be supplied to the pipes L³ from any suitable 50 source as through the branch pipe L⁵ from the steam and water drum K'. A valve L⁴ regulates the supply of steam to each pipe L². A steam supply passage L is provided for each 55 of the combustion chamber channels H¹ throughout the portion of the distillation
- chamber in which the temperatures are high enough to crack the hydrocarbons and cause the deposits of solid carbon on the walls of the channels H¹.
- 60 In the normal intended use of the apparatus, the trucks D are moved slowly through the kiln and the coal carried in the trays D¹ on each truck D, is gradually increased in temperature as the truck moves from the entrance end of the kiln to the portion alongside the end of the combustion chambers at which combustion is initiated. As the coal heats up, the gases and vapors are distilled out of the coal and as these gases and vapors are generated they are withdrawn through the various outlets A¹⁰. The transfer of heat from the combustion chambers to the coal is brought about by the convection currents of the kiln atmosphere as previously indicated. As each truck passes away from the combustion chambers into the zone in which the cooling system K is located, the temperature of the coal or rather coke carried by the truck begins to cool, and the generation of gases and vapors cease. The injection of steam into the most highly heated channels from the passages L, in relatively small amounts prevents the formation of solid carbon particles and the deposit of the latter upon the walls of the channels H¹. If, for a time, the steam supply be interrupted, or be insufficient in amount to prevent the deposit of carbon on the walls of the channels H¹, any deposit of carbon on the channel walls then formed may thereafter be removed by supplying sufficient steam to the 70 passages L for a short period. Advantageously sight holes M into the channels H¹ are provided to permit the inspection of the latter from time to time, to determine from 75 their appearance whether the proper amount of steam is being supplied through the passage L.
- 75 Instead of supplying steam to the kiln in relatively small amounts for the primary purpose of preventing carbon deposits from the cracked gases of distillation, I contemplate in some cases, the introduction of steam in relatively large amounts to secure a quantitative yield of water gas for the unvaporized coke residue of the coal introduced into the kiln.
- 80 For example, the apparatus of Figs. 1 and 2, if suitably proportioned for the purpose, may be so operated that the coal in each car will be thoroughly coked, at least at its surface, while there is a considerable portion of the kiln zone containing combustion chambers, still to be transversed by the car. In such case, steam admitted to the combustion 85 chamber passages H¹ along which the car will pass will be superheated as it rises through those passages and will then pass into contact with the hot coke and will react with the latter to form water gas. To 90

insure a quantitative conversion of the steam into water gas it will be necessary, of course, to prevent the steam or any considerable portion thereof from passing directly to the gas outlets from the tops of the passages H^1 to which it is supplied. This may be accomplished, for example, by closing some of the outlets so that the outlets for the water gas are appreciably nearer the exit end of the kiln than are the passages H^1 supplied with steam for the manufacture of water gas. Under such circumstances, the path of gas flow between the point of steam admission and the outlet for water gas will be a spiral of several turns, the up flow side of each turn being through passages H^1 wherein the steam and gas are heated and the down flow side of each turn being through the goods space wherein the steam or other gas is cooled. This spiral flow is a natural convection current phenomenon and as a result of it, any molecule of steam not converted into water gas on its first downward passage in contact with the coal, may be so converted on a subsequent downward passage.

If the proper amount of steam is supplied and the combustion chambers supply sufficient heat, all the carbon in the coke and all the steam supplied may be eventually converted into water gas. The consumption of coke in the manufacture of water gas is an endothermic reaction in which heat is absorbed. It is to be noted that the supply of heat to the coke by the superheated steam and hot water gas mixed with the coke as well as the coke consumption and consequent coke cooling are both surface actions. The cooling of the coke by its reaction with the steam augments the effectiveness of the convection current heat equalizing reaction in the kiln chamber.

It will be apparent to those skilled in the art that the characteristic Dressler kiln combustion chamber construction shown in Figs. 1 and 2, is especially adapted for use in carrying out the described methods, but these methods may be carried out in any type of muffle heated kilns. In Fig. 3 I have illustrated, by way of example, another type of kiln adapted for carrying out the invention in its broader aspects. The kiln shown in Fig. 3 differs from that shown in Figs. 1 and 2 in that combustion occurs in, or hot gases flow through ducts HA in the side walls of the kiln and heat is transmitted to the kiln atmosphere only from the inner walls H^2 of the ducts HA . A barrier or partition wall P in front of the duct wall H^2 provides a vertical channel P' open at top and bottom for directing the convection current circulation of the chamber atmosphere upward past the wall H^2 . With this arrangement I inject steam into the bottoms of the channel P' through passages L which may be similar to the passages L of the construction first de-

scribed and be supplied with steam in the same manner.

Having now described my invention, what I claim as new and desire to secure by Letters Patent, is:

1. The method of making water gas in a tunnel kiln, which consists in passing coke through the kiln passageway, supplying steam to the kiln passageway and transmitting heat to the coke from an enclosed source of heat at the sides of the passageway by convection currents of the kiln atmosphere. 70

2. The method of distilling coal in a continuous tunnel kiln which comprises passing coal through the kiln passageway, transmitting heat to the coal by circulating the kiln atmosphere through a space partially separated from said passageway and wherein the circulating atmosphere is heated, returning the heated atmosphere to the kiln passageway and mixing a decarbonizing fluid with the portion of the kiln atmosphere passing through said separated space. 80

3. The method of distilling coal in a continuous tunnel kiln which comprises passing coal through the kiln passageway, transmitting heat to the coal by circulating the kiln atmosphere through a space partially separated from said passageway and wherein the circulating atmosphere is heated, returning the heated atmosphere to the kiln passageway and mixing steam with the portion of the kiln atmosphere passing through said separated space. 90

4. The method of distilling coal in a continuous tunnel kiln which comprises passing coal continuously through the main kiln passageway in intimate contact with the kiln chamber atmosphere, circulating the chamber atmosphere transversely of the kiln passageway and in contact with a heated surface at the side of the passageway, and mixing a decarbonizing fluid with the portion of the chamber atmosphere contacting with the heated surface to eliminate carbon deposits. 100

5. A continuous tunnel kiln comprising a kiln chamber having a goods passageway therethrough, an enclosed heating means at the side of said passageway, a passage adjacent said means and connected to said goods passageway to permit the circulation of the kiln atmosphere therethrough in contact with said means, and provisions for passing a fluid decarbonizing agent into said chamber. 115

6. A continuous tunnel kiln comprising a kiln chamber having a goods passageway therethrough, an enclosed heating means at the side of said passageway, a passage adjacent said means and connected to said goods passageway to permit the circulation of the kiln atmosphere therethrough in contact with said means, and provisions for passing steam into said chamber at points adjacent said means. 120

7. A tunnel kiln comprising a kiln cham-

- ber and a combustion chamber therein at the side of a goods passageway through the kiln chamber, said combustion chamber having an open ended channel in a wall thereof and provisions for injecting a fluid agent into said channel to modify the kiln chamber atmosphere.
8. A tunnel kiln comprising a kiln chamber and a combustion chamber therein at each side of a goods passageway through the kiln chamber, each of said combustion chambers having open ended channels in the walls thereof and provisions for injecting steam into said channels.
15. 9. Apparatus for the continuous carbonization of coal comprising in combination a tunnel kiln chamber having a central passage therein, means for moving coal continuously through said passage, a separate combustion chamber structure extending longitudinally of said chamber adjacent said passage, channels formed in said combustion chamber structure at the side of and connected to said passage, and means for injecting a fluid decarbonizing agent into said chamber in proximity to the highly heated portions of the kiln structure.
10. Apparatus for the continuous carbonization of coal comprising in combination a tunnel kiln chamber having a central passage 30 therein, means for moving coal continuously through said passage, a combustion chamber structure extending longitudinally of said chamber at the sides of said passage, a vertical passage adjacent said combustion chamber and connected at its lower and upper ends to said central passage for the circulation of the kiln atmosphere therethrough and provisions for injecting steam into said passage to eliminate carbon deposits in said chamber. 35

Signed at Detroit in the county of Wayne and State of Michigan this 5th day of April A. D. 1920.

PHILIP D'H. DRESSLER.
